UNITED STATES PATENT OFFICE.

AXEL RUDOLF LINDBLAD, OF LUDVIKA, SWEDEN.

METHOD FOR PRODUCTION OF CYANOGEN COMPOUNDS.

1,187,633.

Specification of Letters Patent. Patented June 20, 1916.

Application filed November 17, 1914. Serial No. 872,532.

To all whom it may concern:

Be it known that I, AXEL RUDOLF LINDBLAD, engineer, subject of the King of Sweden, residing at Ludvika, in the Kingdom of Sweden, have invented certain new and useful Improvements in Methods for Production of Cyanogen Compounds.

The present invention has for an object synthetic production of cyanogen compounds or other compounds formed of cyanogen compounds.

Several experiments have been made to produce cyanogen compounds out of carbon and nitrogen through direct synthetic usually in the presence of an alkali compound, or alkaline earth compounds to obtain cyanids or cyanates of metals. This synthesis has appeared possible but for industrial work none of the methods hitherto proposed could be used. The principal reasons are partly that it is difficult to supply the heat necessary for carrying out the reaction which is in a high degree endothermic and partly that the brickwork of the apparatuses used very soon gets spoiled by the influence of the melted alkaline compounds. For this reason the mind was directed on the use of electric furnaces and experiments in that respect have also earlier been made. The results became however equally bad as by the heating in retorts before undertaken, the electric current followed the inner walls of the furnace chamber which had for effect that said walls were burnt down and besides this destroying influence of the alkalis on the furnace material was equally bad as before. According to investigations made by me one of the chief reasons of this negative result consists in the form of the electric furnace which was not suitable for this purpose. Said furnace namely consisted in a cylindrical shaft with carbon electrodes entering through the walls of the same. At the heating of the charge the alkalis contained in the charge melted and flowed down along the walls of the shaft. Melted salts being comparatively good conductors for the electric current, the result was, that only one part of the current flowed the proper way through the charge, while another part flowed along the walls, thereby heating and destroying them. In order to obviate these difficulties according to the present invention an electric furnace is used which is so

constructed that the horizontal sectional area of the furnace chamber at one or several places is greater than at above lying parts of the furnace chamber for which purpose, at that place or places, the furnace chamber is given the form of a cone or a pyramid or another form which fulfills said conditions. Thereby the melted alkalis are hindered to flow down along the walls of the furnace forming a path for the electric current, but the current is forced to flow the way aimed at, whereby the furnace material is preserved against the destroying action of the current.

In order to make the invention more clear there is shown on the accompanying drawing two suitable forms of a furnace for carrying out the present method.

Figure 1 shows one form of the furnace in vertical section and Fig. 2 shows in the same way a somewhat modified form of the furnace chamber.

In the different figures corresponding parts are indicated with the same designation.

The invention is first described with regard to Fig. 1. 1 is the furnace shaft, which at its bottom opens into a wider furnace chamber 2. 3 are the electrodes, through which the electric current is supplied to the charge, 4 are contact members for leading the current to the electrodes, 5 are water-cooled frames intended to strengthen the brickwork at those places, where the electrodes are introduced. 6 are conduits for supply of gaseous nitrogen. 7 is a discharge conduit for gas formed during the process. 8 is a taphole for slag and other materials, being removed from the furnace in liquid form.

As above stated the same designations in Fig. 2 indicate corresponding parts as in Fig. 1.

According to the form shown in Fig. 2 the furnace chamber is given such a form, that one or several free gas spaces will arise between the brickwork of the furnace and the charge sinking down into the same as indicated with dotted lines. As an example of the carrying out of the process, with use of this furnace I will first describe the manufacture of potassium cyanid, KCN, according to the present invention. As raw material I use any suitable potassium

compound for instance potassium carbonate K_2CO_3 or potassium hydrate KOH. The carbon is suitably supplied in the form of charcoal, the gaseous nitrogen ought to be 5 comparatively pure and can be manufactured in any of the usual manners, for instance through fractionated distillation of air. The carbon and potassium compound are introduced through the charging device 10 arranged in the upper part of the shaft. Necessary electric energy is supplied through the electrodes 3, and nitrogen is blown in through the conduits 6. If the temperature is kept sufficiently high by the aid of the 15 electric current, the reaction is going on, if potassium carbonate is used as raw material, substantially according to the formula:

20 or if potassium hydrate is used

Of course the reaction is not going on completely according to these formulas. 25 Smaller quantities of other cyanogen compounds, for instance cyanates, are also formed as well as small quantities of carbon dioxid and other compounds. The formulas above given may therefore only be considered as to state the principal reactions. 30 Generally it is suitable to use so high a temperature, that the cyanogen compounds obtained escape in gaseous state. This is of course not necessary, but involves several advantages, as for instance less impurities in the products obtained, simplified work and so forth. For evaporating the cyanogen compounds it is however not necessary to keep a temperature corresponding to their 35 boiling points. Already at a considerably lower temperature its vapor pressure is so high, that the evaporation is possible. Then they go off in the form of smoke together with the escaping gases. The cyanogen compounds leaving the furnace are condensed and collected in suitable receivers, not shown and not being an object for the present invention.

Under certain conditions it may be 50 able to blow in the gaseous nitrogen only or substantially from the one side. If the outlet for the gases formed is arranged as shown on the drawing, the nitrogen ought to be blown in from the side, located opposite to this outlet, in order thereby to force the nitrogen during a long time to be in contact with the other materials charged into the furnace. Further it may also be advantageous to charge the potassium compound 55 at the one side of the furnace. In Fig. 2 is shown a charging device intended for such a charging.

Analogous to the manufacturing of potassium cyanid also several other cyanids are 60 manufactured, especially the sodium cyanid,

which is nearly related to the potassium cyanid.

Here above the process is described only in the case where the cyanogen compounds form the final products, but the method can 70 of course also be used with the same advantage, even when these compounds only form a middle product, *i. e.* a product from which other products are manufactured, for instance for synthetic manufacture of ammonia. In this case the cyanogen compounds obtained in the above stated manner are decomposed by means of overheated water-steam or in other ways, whereafter the alkali compounds thereby generated are 80 re-introduced into the process. In the case water-steam is used, this part of the process passes on for instance according to the following formulas:

or

If cyanate has been formed as primary 90 product, the reaction is thought to take the following course:

Having thus described my invention, I declare, that what I claim is:

1. A process for the production of cyanogen compounds of the class herein described consisting in charging the material used into a melting chamber of an electric furnace in a downward direction, causing the charge to spread and form outwardly sloping surfaces, supplying electric current to the charge at said sloping surfaces, and introducing gaseous nitrogen into the chamber so that it comes in contact with the charge when heated by the electric current.

2. A process for the production of cyanogen compounds of the class herein described consisting in charging the material used into a melting chamber of an electric furnace in a downward direction to allow the charge to spread and form outwardly sloping surfaces, supplying electric current to the charge at said sloping surfaces, and introducing gaseous nitrogen into the chamber adjacent to the points of electric supply so as to contact with the charge adjacent to the points of supply of the electric current.

3. A process for the production of cyanogen compounds of the class herein described consisting in charging the material used into a melting chamber of an electric furnace in a downward direction to allow the charge to spread and form outwardly sloping surfaces, supplying electric current to the charge at said sloping surfaces, introducing gaseous nitrogen into the melting chamber so that it comes in contact with the charge when heated by the electric current,

the said nitrogen being introduced at one side of the charge, and conducting the cyanogen compounds formed out of the said chamber from the side thereof opposite to 5 the point of introduction of the nitrogen.

4. A process for the production of cyanogen compounds of the class herein described consisting in charging a mixture of carbon and metal compounds into a melting chamber 10 of an electric furnace in a downward direction, causing the charge to spread and form outwardly sloping surfaces, supplying electric current to the charge at said sloping surfaces, introducing gaseous nitrogen into 15 the melting chamber, and leading off the cyanogen compounds formed and collecting the same.
5. A process for the production of cyanogen compounds of the class herein described 20 consisting in charging a mixture of carbon and metal compounds into a melting chamber of an electric furnace in a downward direction, causing the charge to spread and form outwardly sloping surfaces, supplying electric current to the charge at said sloping surfaces, introducing gaseous nitrogen into 25 the melting chamber, leading off the cyanogen compounds formed, and decomposing

the same by means of steam to form ammonia.

6. A process for the production of cyanogen compounds of the class herein described consisting in charging the material used downwardly through the shaft of an electric furnace into the enlarged melting chamber 30 of the same to allow the charge to spread and form outwardly sloping surfaces, supplying electric current to the charge at said sloping surfaces, and introducing gaseous nitrogen into the chamber so that it comes 35 in contact with the charge when heated by the electric current.

7. The herein described process for producing cyanogen compounds which consists in so feeding the charge that it will spread 40 to form outwardly sloping surfaces, electrically heating the charge at the sloping surfaces, and supplying gaseous nitrogen to the charge.

In witness hereof I have hereunto set my 45 hand in presence of two witnesses.

AXEL RUDOLF LINDBLAD.
